UNITED STATES PATENT OFFICE.

WALTER SCOTT, OF PLAINFIELD, NEW JERSEY.

PRINTING-MACHINE.

No. 823,553.

Specification of Letters Patent.

Patented June 19, 1906.

Application filed September 14, 1904. Serial No. 224,355.

To all whom it may concern:

Be it known that I, WALTER SCOTT, a citizen of the United States of America, and a resident of Plainfield, county of Union, and 5 State of New Jersey, have invented certain new and useful Improvements in Printing-Machines, of which the following is a specification.

My invention relates generally to printing 10 or other machines, and has more particular reference to bed motions for a cylinder and bed-printing machine.

The object of the invention is to simplify 15 the structure as much as possible, at the same time obtaining a high efficiency.

Broadly speaking, the said invention consists in the features of construction and combinations of parts disclosed in the more particular description which follows.

20 In the accompanying drawings I have embodied my invention in a suitable form without, however, restricting myself to the exact structure shown.

In the said drawings, Figure 1 is a side elevation of a machine embodying my invention. Fig. 2 shows a modification. Fig. 3 is a plan view of Fig. 1, partly in section. Fig. 4 is a sectional view on the line 4-4 of Fig. 3.

Similar characters of reference indicate 30 corresponding parts in the different views.

1 indicates a framework of any suitable form for properly supporting the parts.

2 denotes the bed provided with the upper and lower racks 3 and 4, with which the driving-gear 5 alternately engages. The general structure of the parts comprising the bed motion so far as certain claims are concerned is immaterial, though the form here shown is similar to the one disclosed in United States

40 Patent No. 322,309, in which a straight shoulder 6 is employed at either end in juxtaposition to an inner shoulder 7, pivoted so as to allow the roll 8, carried by the driving-gear, to engage between the shoulders on the reversal of the bed in a well-known manner.

45 The improvement resides in the means for raising and lowering the driving shaft and gear, so as to cause the latter to engage alternately with the racks on the bed and for operating the said driving shaft and gear.

9 indicates a member or bracket swinging around or pivoted at the center 10 and supporting at its free end, where it is provided with the bearings 11 and 11^a, the driving-shaft 12. The member 9 can be mounted on a rock-shaft or, as shown in the present in-

stance, it is provided with two pivots 13. The member 9 is rocked by some suitable means, as by the arm 14, provided with the roll 15, engaging in the cam 16. The arm 14 60 may be made, as shown, in two parts 17 and 18, adjustably connected, so as to take up any unevenness due to wear. The adjustable connection between the two parts 17 and 18 in the present instance is constructed as follows: The said two parts are pivotally connected by means of the bolt 18 and are further provided the one with a slot 20 and the other with an adjustable bolt 21. 22 and 23 are set-screws passing through the projections 24 of one part and bearing upon the other part whereby the desired adjustment 65 can be effected.

Suitable means for operating the driving-shaft are provided taking in the present instance the following form: The bearing 11^a projects a distance outside the framework and is surrounded by a fixed hub 25, on which the gear 26 is loosely mounted and which is further provided with an axial hole 80 or opening 25^a, somewhat larger than the diameter of the bearing 11^a, so that the latter is free to move up and down inside of the said fixed hub within certain limits sufficient to enable the driving-gear to engage with either 85 the upper or lower rack. The motion is transferred from the gear 26 to the shaft 12 by means of a sliding block and guide connection, preferably constructed, as shown in the drawings, by mounting an arm 27 on the 90 end of the shaft 12, provided with the slot 28, forming a guide-way in which slides the block or member 29, carried by the gear 26.

As the gear 26 rotates, receiving its motion in some suitable way, as from the driving-pinion 30, the sliding block 29, projecting into the guideway 28, will cause the shaft 12 to rotate, thereby causing the driving-gear 5 to engage with one of the racks. The parts are so timed that when the bed comes to the end 95 of its motion in either direction the bracket 9 is moved up or down by the cam 16, as the case may be, this up-and-down motion of the bracket, driving shaft, and gear being free to take place by reason of the large axial hole 25^a 100 in the hub portion 25, while the periodical eccentricity of the shaft 12 with relation to the gear 26 is compensated for by the loose connection of the block and guide, which transmits the motion of the said gear to the 105 said shaft.

In Fig. 2 I have shown a modification in

which the weight of the driving-shaft and the members carried by the same is taken advantage of to cause the roll 31 to bear against the cam-surface 32, while the spring 33 is further utilized to keep the said roll snugly in position against the said inner surface of the cam. The difference between this construction and the one shown in Fig. 1 is simply that in the latter the roll 15 bears against the outer surface of the cam 16 rather than against the inner surface of the same. Of course a spring similar to 33 can also be used in this construction, if desired.

What I claim is—

1. In a printing or other machine, the combination with an upper and a lower rack and a gear adapted to alternately engage with the same, of means for periodically lowering and raising the said gear comprising a pivoted bracket having bearings at its free end, a shaft on which the said gear is mounted supported in the said bearings, an arm carried by the said bracket composed of two parts bolted together at one point, a slot and corresponding bolt on the said two parts at another point, extensions on one of said parts projecting over the other of the said parts, and set-screws passing through the said projections and bearing against the said other part, a roll carried at the end of said arm, and a cam with which the said roll engages.

2. In a printing or other machine, the combination with an upper and a lower rack and a gear adapted to alternately engage with the same, of means for periodically lowering and raising the said gear comprising a pivoted bracket having bearings at its free end, a shaft on which the said gear is mounted supported in the said bearings, means for rocking the said bracket, a stationary hub surrounding one of the bearings of the bracket, a gear mounted on the said hub, and means for transferring the motion from the said gear on the hub to the shaft carried by the bracket.

3. In a printing or other machine, the combination with an upper and a lower rack and a gear adapted to alternately engage with the same, of means for periodically lowering and raising the said gear comprising a pivoted bracket having bearings at its free end, a shaft on which the said gear is mounted supported in the said bearings, means for rocking the said bracket, a stationary hub surrounding one of the bearings of the said bracket having an axial hole somewhat larger than the diameter of the said bearing, a gear mounted on the said hub, and means for transferring the motion from the said gear to the shaft carried by the bracket.

4. In a printing or other machine, the combination with an upper and a lower rack and a gear adapted to alternately engage with the same, of means for periodically lowering and raising the said gear comprising a pivoted bracket having bearings at its free end, a

shaft on which the said gear is mounted supported in the said bearings, means for rocking the said bracket, a stationary hub surrounding one of the bearings of the said bracket, a gear mounted on the said hub, and a guideway and sliding block mounted one on the gear on the hub and the other on the shaft supported by the bearings of the bracket for imparting the motion of the said gear to the said shaft.

5. In a printing or other machine, the combination with an upper and a lower rack and a gear adapted to alternately engage with the same, of means for periodically lowering and raising the said gear comprising a pivoted bracket having bearings at its free end, a shaft on which the said gear is mounted supported in the said bearings, means for rocking the said bracket, a stationary hub surrounding one of the bearings of the said bracket having an axial hole somewhat larger than the diameter of the said bracket, a gear mounted on the said hub, and a guideway and sliding block mounted one on the gear on the hub and the other on the shaft carried by the bearings of the bracket for imparting the motion of the said gear to the said shaft.

6. In a printing or other machine, the combination with an upper and a lower rack and a gear adapted to alternately engage with the same, of means for periodically lowering and raising the said gear, comprising: a pivoted bracket, a shaft on which the gear is mounted supported by said bracket, means for rocking the said bracket, a stationary hub surrounding a portion of the shaft, a gear mounted on the said hub, and means for transferring the motion from the said gear on the hub to the shaft carried by the bracket.

7. In a printing or other machine, the combination with an upper and a lower rack and a gear adapted to alternately engage with the same, of means for periodically lowering and raising the said gear, comprising: a pivoted bracket, a shaft on which the gear is mounted supported by said bracket, means for rocking the said bracket, a stationary hub surrounding a portion of the shaft, a gear mounted on the said hub, and a guideway and sliding block mounted one on the gear on the hub and the other on the shaft carried by the bracket for imparting the motion of the said gear to the said shaft.

8. In a printing or other machine, the combination with an upper and a lower rack, and a gear adapted to alternately engage with the same, of means for periodically lowering and raising the said gear, comprising a pivoted bracket having bearings at its free end, a shaft on which the said gear is mounted supported in said bearings, and means for rocking the said bracket, a gear mounted at the outer end of the said shaft, and a loose driving connection between said gear and shaft.

9. In a printing or other machine, the com-

5 bination with an upper and a lower rack, and a gear adapted to alternately engage with the same, of means for periodically lowering and raising the said gear, comprising a pivoted bracket having bearings at its free end, a shaft on which the said gear is mounted supported in said bearings, an arm carried by said bracket, a friction-roll mounted on the same, and a cam in which the said friction-

roll engages, a gear mounted at the outer end 10 of the said shaft, and a loose driving connection between said gear and shaft.

Signed at New York; this 30th day of August, 1904.
